UNITED STATES PATENT OFFICE.

JOSEPH W. FROST, OF WASHINGTON, DISTRICT OF COLUMBIA.

NECKWEAR.

No. 854,284.

Specification of Letters Patent.

Patented May 21, 1907.

Application filed August 11, 1903. Serial No. 169,087.

To all whom it may concern:

Be it known that I, JOSEPH W. FROST, a citizen of the United States, residing at Washington, in the District of Columbia, have invented certain new and useful Improvements in Neckwear, of which the following is a specification, reference being had thereto to the accompanying drawing.

This invention relates to and is an improvement of what is commonly known as a "four-in-hand" cravat or necktie; that is one which is not normally "made up," and which has two free ends adapted to be folded together in a well known manner. When such a tie is used, especially in connection with a "turn-down" collar, great difficulty is usually experienced in shifting the tie in or over the collar; so much in fact that many individuals cannot wear such a collar at all in connection with the class of tie referred to. The shifting of the tie within the collar is necessary to take up the slack necessarily formed for the purpose of passing the end of the tie upward between the collar and the preliminary folds. These disadvantages and also that of the wear and strain both on the collar and tie occasioned by this shifting and attendant friction, are generally understood and recognized.

The object of this improvement is to overcome these difficulties, and also to cheapen the manufacture of a tie of this character by the use of smaller pieces of textile stock or of "scraps" which the particular construction herein shown, at least incidentally accomplishes.

In the accompanying drawings Figure 1 is a side view of the tie with one side of a portion of the tie end cut away to show a "tip" or stiffened portion; and Fig. 2 represents the tie being made up in connection with a "turn down" collar.

Referring to Fig. 1: The end pieces *a* and *a'* are made of any suitable textile material and constitute those portions of the tie used in folding or tying the same to the collar. These ends are suitably fastened at *b* and *b'* to a piece of band elastic *e*, the same being shown as of one piece of woven textile material made elastic only at the sides *d* and *d'*, but it is apparent it could consist of one solid elastic band. I prefer the construction shown however for reasons to be later given. At *h*, a

buttonhole is shown both for the purpose of fixing a center to the elastic portions and also to be employed as such where the tie is used with a "stand up" collar, for the purpose of holding the same down to the shirtband as such fastening does not interfere with its subsequent make up. The centering of the elastic band is thus conveniently accomplished and keeps the ends of the said band, *b* *b'*, at equal distances from the ends of the collar. At one end of the tie there is suitably fastened between the folds thereof, the tip *e*, the purpose of which will be shown.

Referring to Fig. 2: *g* is an ordinary "turn down" collar with the folds of same inclosing the tie, which is shown as partially made up.

The manner of adjusting or operating is as follows: Before the first lap or fold is made, the ends of the tie are pulled slightly outward, thus causing the rubber bands to stretch. The other folds are then made in the usual well known manner and when it becomes necessary to push the tie end upward between the folded portion and the collar, the tie is again stretched outward with the left hand, thus making room for the passage of the end which is then easily accomplished by taking the end tip in the right hand and inserting it in position. Thus there is no slack to make necessary the shifting of the tie in or over the collar as the case may be. The tip *e* in this connection is of great convenience as it readily enables the necessary action to be taken as well as that of passing the tie end downward and under the outer lap; which is the last move in the completion of the knot.

Other advantages in this form of tie are 90 1st. There is very much less wear and strain on the material and also on the nervous system of the manipulator, than where the tie is with difficulty shifted in or over the collar and 2d. When the principal or tie end 95 (that used to form the bow) becomes soiled or worn, sufficient of the end may be cut away (at *i*) to cause an unworn and unsoiled portion to come into prominence after the tie is made up. Another advantage is that 100 the tension of the rubber has a tendency to keep the tie well up in a "turn down" collar where it should be.

It is plain that many modifications can be made in the construction of the tie without 105 departing from the spirit of this invention.

The end *b*, could be adjustably fastened to the elastic band in many other ways than by sewing; as for instance by clenching them together by metal fasteners or by the use of hooks and eyes, though it seems that sewing would be preferable. The woven elastic band if fastened to a part of the tie ends of greater width than the end of the elastic band proper, could be woven wider at such points *5* and the elastic band could be woven in substantially the same colors as the fabric of which the tie proper is made.

The band *c* is shown elastic at *d* and *d'* because it would be of little use if made so at *15* the extreme back part because of its inability to slip at that point; but as stated it could be made wholly elastic.

In my new article of neckwear it is essential *20* that the neck band portion be made of a length sufficient to embrace the back and side portions of the collar, particularly if the tie is to be used in connection with a collar of the doubled or folded variety known as a "turn down" collar. This neck-band portion *25* is made of thin flat elastic fabric or webbing which is thinner and smoother than the two lengths of textile of which the tie proper is made, and by making such neck band of a length sufficient to fit the back and side portions of the collar, it provides enough elastic *30* material in the neck-band portion to enable the user to draw out the textile ends far enough to fold said textile ends without slipping the neck-band bodily through the folded or doubled turn down collar when tying the *35* article. I have found it desirable to use in the neck-band an elastic webbing from six (6) to ten (10) inches long, in order to secure an article of neckwear which may be tied *40* without shifting the neck-band bodily in the collar, as contemplated by my invention. It is to be understood, therefore, that my new article comprises neckwear made of at least three lengths or sections, two of which *45* are of the usual textile material and the elastic neck-band portion of which is long enough to fit around and engage with the side portions of a turn down collar, said elastic neck-band being composed of a material different from that of the free end portions of the tie.

Another advantage in my preferred form of article consists in the use of a neckband *55* made up of a non-elastic middle portion and elastic end portions, the latter being united to the end lengths of textile fabric, and said non-elastic length of the neck-band being provided with means for engagement with a collar button. This construction allows the *60* neck-band to be secured in position in order to center the tie within a folded collar, and the elastic portions of the neck band permit the operator to draw out the individual textile portions of the tie in the operation of

tying the same. The non-elastic section *c* *65* of the neck-band enables me to use the buttonhole tab *h* in a position where it may easily be grasped in order to attach it to the collar button.

The designation "free ends" or "tie ends" *70* used in the appended claims should be interpreted as meaning tie ends made of textile fabric and which are not normally, and need not be, fastened in any manner as they project from the sides of the collar.

What I claim is

1. As a new article of manufacture, a necktie or cravat consisting of two end lengths of textile fabric, and an elastic neck-band portion suitably joined to the same, said elastic *80* neck-band portion being of a sufficient length to engage the sides of the collar, whereby the said necktie or cravat may be made up without shifting it bodily through the collar, substantially as described.

2. As a new article of manufacture, a necktie or cravat consisting of two end lengths of textile fabric, and a flat elastic neck-band portion suitably joined to the same, said neck-band portion being of a sufficient length *90* to engage the sides of the collar, whereby the said neck-band or cravat may be made up without shifting it bodily through the collar, substantially as described.

3. As a new article of manufacture, a necktie or cravat consisting of two tie end pieces of textile fabric, a neck-band of elastic material, said elastic neck-band being adapted to engage the respective side portions of a collar, and suitable means for connecting the respective ends of said elastic neck-band to the textile tie end pieces, whereby the said necktie or cravat may be folded or made up without shifting the same bodily through the *100* collar.

4. As a new article of manufacture, a necktie or cravat consisting of two end lengths of textile fabric and a neck-band portion, said neck-band portion comprising two flat strips of elastic material each joined at one end to *110* the said end lengths, and adapted to engage the side portions of the collar, said flat strips of elastic material being connected at their opposite ends by a third piece of textile fabric, whereby the said necktie or cravat may be made up without shifting it bodily through the *115* collar.

5. As a new article of manufacture, a necktie or cravat consisting of two end lengths of textile fabric, and a neck-band portion, said *120* neck-band portion comprising two strips of elastic material each joined at one end to the said end lengths and adapted to engage the side portions of a collar, said strips of elastic material being connected at their opposite *125* ends by a third piece of textile fabric, whereby the said necktie or cravat may be made up without shifting it bodily through the collar.

6. As a new article of manufacture, a necktie or cravat consisting of two tie ends of a textile fabric, which are suitably joined, each to one end of two pieces of elastic material adapted to engage the sides of the collar, and suitable means for connecting the two opposite ends of said elastic material in operative relation.

In testimony whereof I have affixed my signature in presence of two witnesses.

JOSEPH W. FROST.
